[57] CLAIM

The ornamental design for a holder for bingo sheets or the like, as shown and described.

DESCRIPTION

FIG. 1 is a front elevation view of a holder for bingo sheets or the like showing the new design; the dashed lines on the holder indicate fold lines and the broken line showing bingo sheets is for illustrative purposes only.

FIG. 2 is a perspective view thereof in a partially folded position.

FIG. 3 is a perspective view thereof in a completely closed position.

The opposite side of FIG. 1 is similar to that shown.

FIG. 3
